UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,228,558.

Specification of Letters Patent.

Patented June 5, 1917.

Application filed May 17, 1913. Serial No. 768,300.

To all whom it may concern:

Be it known that I, RUSSELL HUFF, a citizen of the United States, and resident of Detroit, Wayne county, State of Michigan, have invented certain new and useful improvements in Hydrocarbon-Motors, of which the following is a specification.

This invention relates to hydrocarbon motors, and particularly to the oil pump and strainer construction.

One of the objects of the present invention is to provide in the bottom of the motor crank case an oil pump and strainer support which may be detached as a unit from the outside of the crank case.

Another object of the invention is to provide an oil pump and strainer support in the bottom of a motor crank case and so construct and assemble the pump and strainer that the pump is detachable from the inside of the support and the strainer is readily detachable from the outside thereof. Suitable passages are formed in the support between the pump and strainer chambers.

Another object of the invention is to detachably secure the strainer to the outside of the bottom of the motor crank case, so that the strainer may be readily removed and cleaned and reassembled.

Other objects and features of the invention will appear from the following description, taken in connection with the drawings which form a part of this specification, and in which,

Figure 1 is a transverse section through the bottom half of a motor crank case, showing the pump and strainer in section;

Fig. 2 is a plan view of the pump and strainer support removed from the crank case; and

Fig. 3 is an elevation view of the pump and strainer shown in Fig. 2.

Referring to the drawings, 10 represents the lower half of a crank case of a hydrocarbon motor in which there is formed an opening 11 which is closed by a cover or support 12 which thereby forms in effect part of the bottom wall of the crank case. The cover 12 is preferably bolted to the case, as by bolts 13, so that it is removable therefrom as a unit.

The cover or support 12 is mostly of double walled construction, and one end of it houses a gear pump 14 between its walls 15 and 16, the latter wall preferably being the inside wall and removably secured to the body part of the support 12, as by the screws 17. The pump 14 is shown as having a squared shank 18 for one of its gears and this shank is adapted to be inserted in the lower end of a square tube 19 when the support 12 is placed in position. The tube 19 is driven from the motor through any suitable driving mechanism, not shown in the drawings.

The other end of the support 12 is formed with openings 20 and 21 in its separated walls, the opening 20 being slightly smaller than and in line with the opening 21. In this end of the support, the strainer is supported and the screen 22 is of inverted cup form and extends upwardly from the opening 20 and is formed with a flange 23 which is slightly larger than the opening 20 but smaller than the opening 21, so that the cup shaped screen may be inserted upwardly through the opening 21 into the position in which it is shown in Fig. 1 of the drawings. This screen 22 may be suitably built up of a frame-work 24 upon which the screening material proper is soldered or otherwise fastened.

An inverted cup shaped protector 25, slightly larger than the screen 22, is placed over the screen, as shown in Fig. 1, and is provided with a flange 26, which is also slightly larger than the opening 20 but smaller than the opening 21, so that the protector may likewise be inserted through the opening 21. The protector 25 is provided adjacent its flange with a series of openings 27 through which the oil in the bottom of the crank case may pass to reach the screen 22. This protector prevents the splashing of oil in the crank case from stirring up the sediment that may collect around the screen, so that this sediment is not thrown up on to the pistons and other bearings within the crank case.

It will be seen that the flanges 23 and 26, above described, form gaskets against the inner face of the circular flange 28 which forms the opening 20, and these

flanges 23 and 26 are pressed against said face by a cover 29 which closes the opening 21 and has a part 30 in contact with the lower face of said flange 23. The cover 30 is secured in place by a clamping arm 31 extending across the outside of the cover in contact with a central point of the cover, as at 32, the clamp being pivoted at 33 to a lug 34 formed as an integral part of the support 12 and detachably secured at its other end to an integral extension 35 formed on the support 12. This latter connection comprises a bolt 36 pivoted to the end of the clamp 31, as at 37, and a nut 38 for drawing up on the bolt.

It will be seen that the cover 29 is of hollow construction and provided with openings 39 in its side walls, so that together with the space 40 it forms a chamber beneath the screen 22 and this chamber is in communication with the inlet side of the pump 14 by a conduit or channel 41 formed in the support 12.

From the above description of the drawings, it will be understood that the oil in the crank case 10 accumulates in the bottom thereof and passes through the openings 27 and the screen 22 into the chamber beneath the screen. The oil is then drawn from this chamber through the passage 41 and into the pump 14 where it is discharged through a pipe 42 and led to various bearings of the motor to be lubricated. In most systems of this character the oil is drained from the bearings and returned to the crank case so that it keeps up a constant circulation.

It will be understood also that the entire support 12 may be removed as a unit with the pump and strainer intact by removing the bolts 13, and that the strainer parts may be removed for cleaning while the support is in place on the bottom of the crank case simply by loosening the nut 38, swinging the bolt 36 away from the extension 35, and dropping the clamp 31 from contact with the cover 29. The cover may then be removed and with it the screen 22 and the protector 25. The parts may then be cleaned and as readily reassembled by the reverse operation.

A specific embodiment of the invention has been described in detail, and will be specifically claimed, but it will be understood that the invention is not limited to the exact details of construction shown, as it will be apparent that changes may be made without departing from the spirit or scope of the invention.

Having thus described my invention, what I claim and desire to secure by Letters Patent is:

1. The combination with a motor crank case having an opening therein, a detachable cover for said opening, a pump detachably fastened to the inside of said

cover, and a strainer detachably secured to the outside of said cover, said cover having a passage between said pump and strainer.

2. A strainer comprising a supporting portion having double walls and registering 70 openings therein, a cover for one of said openings, a screen secured over the other opening by said cover, and means for securing the cover in position.

3. The combination with a motor crank 75 case having an opening therein, of an inverted cup shaped screen extending upwardly from said opening and having a flange in contact with the edge of said opening, a cover for said opening beneath said 80 screen and having a part in contact with the flange of said screen for securing the screen in position, and means on the outside of the crank case for holding the cover in place.

4. The combination with a motor crank 85 case having an opening therein, of an inverted cup shaped screen extending upwardly from said opening and having a flange in contact with the edge of said opening, a cover for said opening beneath said 90 screen and having a part in contact with the flange of said screen for securing the screen in position, and means on the outside of the crank case for holding the cover in place, comprising a swinging clamp extending 95 across the cover and pivoted at one side thereof and detachably secured at the other side thereof.

5. The combination with a motor crank 100 case having an opening in the bottom thereof, of an inverted cup shaped protector extending upwardly from said opening and having a flange in contact with the edge of said opening, an inverted cup shaped screen arranged within said protector, a cover for said opening beneath said screen and having a part adapted to secure said screen and protector in position, and means on the outside of the crank case for holding said cover in place.

6. The combination with a motor crank 105 case having an opening in the bottom thereof, and a detachable cover for said opening, of a screen secured in said opening, a protecting device over said screen having openings for the oil to pass to the screen, and means for detachably securing said screen and said device to the outside of said cover.

7. The combination with a motor crank 110 case having an opening therein, of a double-walled cover therefor, said cover having openings in the upper and lower walls, a strainer secured in the opening in the upper wall, and a cover mounted in the opening 115 in the lower wall.

8. The combination with a motor crank case having an opening therein, of a double-walled cover therefor, said cover having openings in the upper and lower walls, a 120

strainer secured in the opening in the upper wall, a cover mounted in the opening in the lower wall, an oil pump mounted between the walls of the first named cover and 5 a channel connecting said pump with said strainer.

9. The combination with a motor crank case having an opening therein and a detachable cover for said opening, of a screen 10 secured over said opening, a protecting device over said screen having openings for

the oil to pass to the screen, said screen and said device being detachably secured together and removable from the crank case through the opening therein.

In testimony whereof I affix my signature 15 in the presence of two witnesses.

RUSSELL HUFF.
